UNITED STATES PATENT OFFICE.

JAMES M. EDER, OF NEW YORK, N. Y.

COMBINED SMOKING-TUBE AND CIGAR-HOLDER.

SPECIFICATION forming part of Letters Patent No. 624,768, dated May 9, 1899.

Application filed September 21, 1898. Serial No. 691,532. (No model.)

To all whom it may concern:

Be it known that I, JAMES M. EDER, of the city of New York, borough of Manhattan, in the county of New York and State of New York, have invented a new and Improved Combined Smoking-Tube and Cigar-Holder, of which the following is a full, clear, and exact description.

This invention relates to improvements in combined smoking-tubes and cigar-holders; and the object is to provide such a device with a simple and convenient means for charging the device with tobacco or a cigar and also for discharging the ashes of the tobacco or the stump of the cigar.

I will describe a combined smoking-tube and cigar-holder embodying my invention and then point out the novel features in the appended claims.

Reference is to be had to the accompanying drawings, forming a part of this specification, in which similar characters of reference indicate corresponding parts in all the views.

Figure 1 is a partial side view and partial section of a combined smoking-tube and cigar-holder embodying my invention. Fig. 2 is a longitudinal section thereof, and Fig. 3 is a partial section and partial side view showing the parts in a different position from that indicated in Fig. 2.

Referring to the drawings, 1 designates the body portion of the smoking-tube or holder, and 2 the mouthpiece thereof. Affixed to the end of the body portion 1 is a sleeve 3, and in this sleeve the mouthpiece 2 is designed to rotate and also to have a slight longitudinal movement. Arranged within the body portion 1 is a spiral wire 4, having a stem portion 5 connected with the mouthpiece 2. As here shown, the said stem portion is connected with the mouthpiece by means of a pin 6, extended through said mouthpiece and also through an eye formed at the end of the stem. One end of the pin 6 is extended slightly outward from the mouthpiece and is adapted to move in a channel 7, formed in the sleeve 3, and it is also adapted to engage in segmental recesses 8, formed in said sleeve for the purpose of holding the end of the mouthpiece

tightly against the end of the body portion. 50 The spiral is of such a diameter as to fit closely in the body portion and extends to the mouth or inlet end of the body portion, so that it acts as a feeder to draw the tobacco in and fill the entire tube or body portion. 55

In operation when it is desired to fill the body portion with tobacco the mouthpiece is to be drawn away from the body portion, as indicated in Fig. 3. Then by holding the body portion in the tobacco and rotating the mouthpiece relatively to the body portion the feeder 4 will be rotated and draw the tobacco into the tube or holder. After filling the tube or holder the mouthpiece is to be moved against the body portion and then slightly rotated to 65 move the ends of the pin 6 into the recesses 8, which will cause the mouthpiece to engage closely against the body portion to prevent the entrance of air. Obviously a reverse movement of the feeder will discharge any 70 ashes that may be contained in the tube or holder. A cigar may be fed into the holder in the same manner as above described and the butt discharged therefrom in the manner above described. 75

While I have shown and described the mouthpiece as being movable relatively to the body portion, it is obvious that the body portion may be movable relatively to the mouthpiece without departing from the spirit 80 of my invention, and it is also obvious that other means may be employed for fastening the feeder to the mouthpiece.

Having thus described my invention, I claim as new and desire to secure by Letters 85 Patent—

1. A combined smoking-tube and cigar-holder, comprising a body portion and a mouthpiece mounted to rotate one relatively to the other, and a spiral-wire feeder in the 90 body portion and having connection with the mouthpiece, the said spiral being extended to the mouth or inlet end of the body portion and having a diameter to fit closely in the body portion, substantially as specified. 95

2. A combined smoking-tube and cigar-holder, comprising a body portion and a mouthpiece mounted to rotate, one relatively

to the other, a spiral feeder arranged in the body portion and extended the entire length thereof, a transverse pin in the mouthpiece and with which the feeder connects, and a 5 sleeve connection between the body portion and mouthpiece, the said sleeve having a channel in which the projected end of said

pin is designed to engage, substantially as specified.

JAMES M. EDER.
